UNITED STATES PATENT OFFICE

2,387,927

METHOD AND APPARATUS FOR MANUFACTURING POTTERY WARE

William J. Miller, Swissvale, Pa., assignor to Miller Pottery Engineering Company, Swissvale, Pittsburgh, Pa., a corporation of Pennsylvania

Original application February 24, 1943, Serial No. 476,939. Divided and this application January 13, 1944, Serial No. 518,080

25 Claims. (Cl. 51—55)

This invention relates to methods and apparatus for manufacturing potteryware, particularly dinnerware, such as plates, saucers, dishes and the like. It has to do with the removal of protuberances hereinafter called "burr" from the backs of glazed, fired ware of the class described.

This application is a division of my co-pending application Serial No. 476,939 filed February 24, 1943.

The most common type of burr is known as a sagger pin burr. Dinnerware is usually fired in saggers which are large containers made of clay capable of holding several pieces of ware. Fire clay pins hereinafter called "sagger pins" inserted in holes in the wall of the sagger are used to support the ware so that the glaze will not be unduly injured during firing. Sagger pins are triangular in cross-section so that they contact the ware as little as possible and three pins spaced at approximately 120° apart are used to support each individual piece of ware, although the spacing may not be exact and the point of contact may not be the same for any two pieces.

Other types of burrs or unwanted protuberances which project above the level of the surface of the ware are produced by stray bits and scraps of clay which escape the sponger's notice and become glazed over in firing and there may be other causes of burrs of which I am not aware.

During firing, the glaze melts and becomes soft 30 allowing the pins to sink in thereby displacing the glaze and raising protuberances which take a permanent set when the glaze cools and hardens. As a rule, the glaze and pin become bonded together and a piece of the pin breaks off when the 35 ware is removed from the sagger. These "burr" while they are not large are nevertheless unsightly and detract from the appearance of the ware. If the burrs contain pieces of sagger pins, they are apt to have sharp, ragged edges which can cut 40 and injure the fingers.

Heretofore, it has been customary to laboriously chip off these hardened burrs by hand using an implement such as a chisel. Burrs do not come off easily and care must be taken against breaking the fragile ware. In the cheaper grades, the product is passable and therefore merchantable if only the top of the burr is knocked off and the sharp, ragged edges smoothed off. This leaves the 50 surface of the ware somewhat less unsightly. In the case of high-grade ware, such as china or porcelain, the last vestiges of the burr are removed by grinding them down to the surface of the ware or almost to the surface. Care must be taken not to grind off or scarify the glaze surrounding the burr because this produces a permanent blemish and therefore the root of the burr may remain but it is hardly noticeable, in fact, the back of the piece will have a smooth 60

appearance and will, of course, not be injurious to the fingers.

Being done by hand, the work is slow and tedious and the average pottery is compelled to employ 5 large numbers of chippers and grinders in order to keep pace with production throughout the balance of the plant. The advent of high-speed, mass-producing forming and drying machinery, such as that in my Patent No. 2,046,525 and the increased out-put of ware resulting therefrom has created the need for efficient time and labor-saving machinery and practices in what I shall call the "ware dressing department" where the sagger pin burrs are removed, this in order to place production in the aforesaid department of the pottery on a equal footing with the fabricating department both from the standpoint of economy and production capacity and otherwise.

Therefore, one object of this invention is to provide new and improved labor-saving methods and apparatus for dressing the backs of glazed, fired ware with precision and despatch to thereby render the ware devoid of burrs and smooth to the touch and sightly to the eye.

Another object is to provide for economically and expeditiously dressing large quantities of ware of various sizes and shapes with a minimum of time and labor.

Still another object is to relieve the average pottery of a potential "bottleneck" in the ware dressing department.

In the drawings:

Fig. 1 is an elevation showing a manually-controlled and operated machine embodying the principles of my invention.

Fig. 2 is a fragmentary plan view of the machine of Fig. 1.

Fig. 3 shows a modified form of the jaw chuck structure illustrated in Fig. 2.

Fig. 4 is a bottom-plan view of the dressing device illustrated in Fig. 1.

Fig. 5 is a fragmentary view in perspective of one of the dressing tools illustrated in Fig. 1.

Fig. 6 is a horizontal section taken on the line 6—6 of Fig. 1.

Fig. 7 is a horizontal section taken on the line 7—7 of Fig. 1.

Fig. 8 is an enlarged vertical section taken on the line 8—8 of Fig. 1.

Fig. 9 is a plan view of the apparatus illustrated in Fig. 8 with certain of the parts broken away.

Fig. 10 is an enlarged detail of one of the tool carriers shown in Fig. 1 with another form of tool thereon.

Fig. 11 is a detail section taken on the line 11—11 of Fig. 10.

Fig. 12 is an enlarged sectional detail of the tool and associated parts seen in Fig. 11.

Fig. 13 is an enlarged view partly in section and

partly in elevation of another form of dressing tool.

Fig. 14 is a view partly in section and partly in elevation of still another form of dressing tool.

Fig. 15 is a bottom plan view of the tool shown in Fig. 14.

Fig. 16 is an enlarged view in section of a portion of a piece of ware as taken across one of the burrs.

Figs. 17 and 18 are fragmentary sectional views illustrative of the appearance of burrs after they have been dressed by chipping and grinding respectively.

The operation of removing "burrs" is one which I shall refer to as that of "dressing" the ware.

The glaze which covers the ware provides a hard-transparent wear-resistance surface not ordinarily marred or scratched by chipping tools which are in the nature of edged implements that slide over the surface of the ware and shear off the burr. On the other hand, glaze can be scrapped and marred by grinding and therefore any grinders disclosed herein will have the grinding wheel supported slightly above the glazed surface of the ware and out of contact therewith so that during relative rotation a line or circle will not be cut into the glazed surface. These various tools which I employ for removing the burrs will be generally referred to as "dressing tools."

It has been mentioned that the ware rests on three sagger pins during firing and that the pins are spaced apart in order to provide a three-point support for the ware. The point of contact of the pins with the ware may or may not be equidistant from the center of the ware. Ordinarily, these points of contact as represented by the burrs on the glazed article are found to fall some place within an inch or so of the brim. Therefore, the location of the burrs in a radial direction from the center of the ware is variable as between the burrs found on a single piece of ware and as between the burrs found on two identical pieces of ware. The machinery of the present invention is designed to compensate for this variable factor.

In the average pottery, the ware is unloaded from the kiln and placed on a conveyor which delivers the fired material to the dressing department. In the dressing department, the manual workers are ranged alongside the conveyor which carries the ware in an endless circuit past the kiln and through the dressing department until the ware is eventually removed by the dresser and processed. It is customary for the dresser to sit on a low stool because the ware is usually handled in stacks of a dozen or so pieces that are heavy to lift. Being close to the floor, the dresser does not have to lift the ware so high and therefore does not become so fatigued as if the ware had been lifted to a table height. The machine of Fig. 1 is designed rest on the floor and to be operated by a dresser while sitting on a low stool as is customary. The machine of Fig. 1 may be placed on a table or on legs and operated from a standing position.

The machine of Fig. 1 is designed to handle one piece of ware at a time, that is to say, it is equipped to dress a single piece of ware at a time.

With reference to Fig. 1, the machine illustrated therein which I shall call a "manual machine" has a base 1 with uprights 2 and 3 supporting a horizontal frame member 4. Reciprocably and rotatably mounted in space bearings 5 and 6 is a vertical shaft 7 carrying the chuck 8, Figs. 1 to 7, arranged to be raised and lowered to move an

inverted piece of ware 9, for instance a saucer into and out of cooperate relation with overhead dressing apparatus 10 to thereby remove the burrs from the back of the ware upon relative rotation 5 between the ware and the dressing apparatus. The machine illustrated in Figs. 1 to 9 is equipped to rotate either the ware or the dressing tools, either one or both depending on the operator's choice.

10 The chuck 8, Fig. 8, includes a disc-like base 14 having a hub 15 on the top end of which is centrally supported a ware positioning disc 16 of which a number may be provided for various sizes of ware. Said discs are detachably mounted on the chuck base and have a taper bore 17 to be received over the conical head 18 of a screw 19 for holding the chuck base on the end of the shaft 7.

Ware is placed on the disc 16 with the chuck in lowered position as shown in dot and dash lines in Fig. 8. When the ware is placed on the disc, it forms with a depression 20, in the disc 16, a chamber 21 which is vacuumized when the chuck is raised to grip the ware to the disc. A central passage 22 in the shaft 7 communicates with chamber 21 and a lateral port 23 connected to a vacuum line 24 through the internal annular port 25 of a stationary valve 26 surrounding the shaft 7, the arrangement being in the nature of a slide valve. When the chuck is lowered, the valve 21 30 is vented to release the ware piece by opening the port 23 to atmosphere. An effective vacuum seal is provided around the brim of the ware by thin rubber disc 30 clamped on the hub 15 by screw 19. As seen in Figs. 8 and 9, the positioning disc extends beyond the hub 15 and the sealing disc 30 normally rests upon radial fins 31 of the chuck base 14. This arrangement permits depression of the seal disc so that the dresser may insert the fingers of the hand under the edge of the ware 40 to remove the ware from the chuck.

As a substitute for, or in addition to the disc 16, the ware may be held in centrally located position on the chuck by a jaw chuck comprising a plurality of arms 32 grouped in a circle 45 on the chuck base and arranged to swing into the ware-holding position as the chuck is raised. The fingers are rotated on their pivots 38 into and out of ware-centering and holding position in response to elevation and lowering of the chuck 50 shaft. The apparatus for causing such movement of the fingers includes a stationary cam 33, Fig. 8, on the bearing 6, a spring-pressed lever 34, Fig. 7 fulcrumed on the under side of the base, a gear segment 35 attached to the lever 55 and mounted on the lever pivot and meshing with a rotatable gear 36 on the hub of the chuck base and gear segments 37 meshing with gear 36 secured to pivot shafts 38, Fig. 1. Shafts 38 are mounted in bearings near the edge of the 60 chuck and the gear segments 37 are below the chuck and the fingers 32 are above the chuck, as illustrated.

The lever 34 may be mounted on the hub of the gear segment 35, see Fig. 7 for angular adjustment by means of a set screw 40 to permit adjustment of the jaws to actuate ware of different diameters. The fingers are resiliently urged into engagement with the edge of the ware by a compression spring 44 acting on the lever 34 and backed up by an adjustable stop 45, or screw in a lug 46 of the chuck base to regulate the pressure engagement of the fingers. The fingers are preferably rubber-tipped as at 45' to prevent injury to the edge of the ware. In the case of ripple-edged ware, each finger may be

provided with a contact shoe 47a, Fig. 3, preferably made of hard rubber and pivotally connected to the finger. Such shoe is self-aligning.

The chuck is raised and lowered by a foot-operated lever 48, Fig. 1 in the form of a bell-crank pivoted on the machine frame. The other arm of the bellcrank is connected to a collar 50 pinned to the shaft 7 and rotatable therewith and pivoted on the pin. When the foot lever is released, the chuck is raised by an enclosed spring 51 which engages the piston 53 on shaft 7. The reduced lower end of the shaft is carried in the bushing 52. During the final upward movement of the chuck, its rate of travel is rotated in order to gently engage the work with the tools. This is accomplished by the retarded dissipation of vacuum created in the cylinder as the piston 53 enters the reduced upper end thereof.

The rate of retarded upward movement of the chuck may be regulated by a port vent 55 and valve 56.

When the chuck is raised, it may be rotated by means of a weight 60 which transmits rotation to the shaft 7 through a cable 61 wound about a pulley 62 on a sleeve 63 supported in the bearings 5 about the shaft 7 and transmitting rotation to the shaft from the pulley through a sliding key connection 64 with the shaft and a pawl and ratchet connection 65 with the pulley. The weight end of the cable is supported over an idler 66 and its other end is connected with a top end of a lever 67 having an abutment 68 arranged in the path of the foot lever 48 to be operated thereby when the chuck is lowered and the weight 60 raised. When the foot lever is released, the cable 61 is held taut about the pulley 62 by a spring 69 which pulls on the lever 67 with less force than the weight. The weight 60 reciprocates in an upright cylinder 74 having an air intake port 75 controlled by a check valve 76 and a vent 77 controlled by a valve 78 whereby the weight may be readily raised and its descent controlled to regulate the rate of rotation of the chuck. The weight 60 may have an upright stem 79 on which may be placed any number of added weights 80 to thereby regulate the speed of rotation of the chuck.

The dressing apparatus 10, Figs. 1 to 4, inclusive, includes a number of tools 84 arranged in a circle about the axis of the ware in the path of the burrs. One tool may be set to strike off burrs in a given path and the next tool set to strike off burrs in an adjacent path, it being remembered that the burrs are not equi-distantly spaced in a radial direction from the axis of the ware. If desired, the tools may be of sufficient length to span the entire zone where the burrs normally occur as will be later explained.

Each tool is carried by a horizontal arm 85 pivoted at 86 on a side of a supporting hub 87 centrally located over the chuck and carrying adjustable spring-pressed stops 88 engaging lever extensions 89 of the arms to resiliently resist downward movement of the arms about their pivots. For regulation, each stop may be in the form of the head of a bolt 90, see Fig. 10, slidably in a sleeve 91 threaded in bearing 92 of the hub 87 with a coiled spring 93 adjustably held under compression between the sleeve and bolt head by nuts 94 on the bolts engaging the sleeve. After the spring has been adjusted for compression by shifting the 75

bolt in the sleeve 91 the head of the bolt may be returned to its original or desired position in determining the normal position of the arm by adjusting the sleeve in the bearing 92 and locking same by means of a locknut 95 thereon.

The tools are mounted on the arms by means of wing nuts and bolts 96 which pass through longitudinal slots 97 and 98 in the arms and tools respectively whereby the tools may be adjusted 10 angularly crosswise and longitudinally on the arms to operate on ware of various sizes and contour.

To reduce operation interference and increase the efficiency of the apparatus, each tool may comprise a shank portion 102, see Fig. 5 slotted at its lower end as at 103 to form jaws 104 recessed at 105 to receive a blade 106 clamped therebetween by a screw 107 passing through the jaws. The blade 106 may have a straight edge for chipping off the burrs or the chipping edge may be contoured if the ware is in the zone where the burrs occur. The blade 106 is preferably composed of hard material such as Carboloy and is preferably rectangular in cross section to provide sharp-cutting edges 108 which may be changed around in obvious fashion as the edges dull.

The hub 87 carrying the arms 85 is mounted on the bottom end of a shaft 111 supported in a bearing 112 on a horizontal extension of bracket 30 113 of cylindrical form mounted for vertical adjustment of a pedestal 114 to elevate or lower the entire dressing apparatus with respect to the ware.

If it is desired to rotate the ware only and to 35 hold the dressing tool stationary, a set screw 115 in the bearing 112 may be tightened against the shaft 111 and the means for rotating the shaft 111 disconnected. If it is desired to rotate the dressing tools rather than the chuck, a set screw 40 116 on the bearing 8 may be used to lock the sleeve 63 therein with the weight 60 in raised position, a set screw 117 in the wall of the cylinder 74 being provided to hold the weight inactive.

The dressing tools are rotated in the following 45 manner: a motor 118 mounted on the bracket 113 drives a crank 119 through a variable speed pulley and belt drive 120. The crank operates a rack 121 which is reciprocated and supported in a guide 122 swiveled on the bearing 112 and a gear 123 on shaft 111 meshing with the rack. The motion produced is an oscillating motion which has certain advantages, however, it should be perfectly clear that the motor shaft may be extended and the pulley 120 raised to the level of 55 the gear 123 which may be removed and replaced by pulley. A belt may connect the two pulleys in order to directly drive and continuously rotate the dressing tools.

Oscillating the tools or the ware for that matter has a distinctive advantage in that a burr 124, 60 see Fig. 16 may be stuck on opposite sides by the tool. In case a portion of the burr may be knocked off when hit on one side, the balance of the burr may be knocked off by striking it on the other side. It will be understood that the tool suspension is such that the tool may raise and ride over a stubborn burr and it may require repeated blows on the part of the tool or tools to dislodge and remove the burr. If the tools or ware are rotated 65 in one direction only, the burr may be struck successively by the same tool or by different tools, and if the tools or ware are simply oscillated, the burr may be struck on both sides by the same tool or by the several tools. This act of chipping away 70 at the burr by delivering repeated blows thereto

will eventually shear away the burr down to the normal surface level of the back of the ware, leaving it smooth and slightly in appearance.

The action thus far described employed to remove the burrs has involved chipping or shearing away by means of an edged tool however, the burr may also be ground down by an abrasive tool which may be substituted for the edged tools or may be operated in conjunction with the edged tools by substituting an abrasive tool for one of the edged tools.

The abrasive tool preferably employed with the machine of Fig. 1 is illustrated in Figs. 10, 11 and 12 and is shown as comprising a grinding wheel 130 mounted on a motor shaft 131 driven by a motor 132. The base 133 of the motor is attached to the lower end of a slotted bracket 135 by universal joint 134. The bracket 135 is mounted on the arm 85 in the same fashion as the arm 84 carrying an edged tool is mounted thereon.

One of the sides of the grinding wheel is used to remove the burrs rather than the periphery of the wheel. In Fig. 10, the wheel is centrally recessed at 136 so as to countersink the attached nut. The abrasive wheel grinds at an angle relative to the surface of the ware and the degree of angularity may be such that the burr is progressively ground off as the wheel travels over the same, this being illustrated by the relative position of the ware and the grinding wheel in Fig. 10.

It has been mentioned that the grinding wheel does not contact the surface of the ware and while it could probably be adjusted so that it would not touch, there are sometimes variations in ware thickness of fractional proportions which would result in the wheel coming in contact with the ware. In order to avoid this, a metal shield may be thrown around the grinding wheel and projected fractionally below the cutting surface in order to space the cutting surface slightly above the surface of the ware. The shield or guard is preferably composed of hard metal having its ware-contacting surface ground down smooth so that it will slide over the surface of the ware without marring or scratching the same. This shield due to its hardness and edged character may also act to deliver a blow to the burr or to the vestiges of the burr to further tend to dislodge the same. Therefore, this tool may be considered as a combination grinding and chipping tool. Said guard is in the form of a sleeve whose bottom edge 139 is preferably tapered inwardly. It is threaded on a sleeve of the motor base 143, Fig. 10, for adjustment to compensate for wearing off the grinding surface of the ware. The locknut 141 on the stem 140 holds the guard in adjusted position.

The motor 132 may be energized from a main power line 142 by distributor 143 on the hub 87 and conductors 144 leading to a rheostat 145 thereby regulating the speed of rotation of the grinding wheel.

Another form of rotating tool that may be employed on the motor shaft 131 is shown in Fig. 13. This tool has a cylindrical head 146 provided with a plurality of blade-like burr removing implements 147 having cutting edges 148 which rest on the surface of the ware as the tool is rotated. The tools will rotate over two points of the path of travel of the burrs and strike them on one side and then on the other in rapid succession in order to completely remove said burrs.

Blades 147 may be made of a very hard substance such as Carboloy and they are retained in slots 149 in the periphery of the head of 146 by screws 150 whose heads overlap the slots. The

blades are adjustable in the slots for alignment with their cutting edges by set screws 151 in threaded bores 152 extending within the slots. Guards 138 are not used with this type of dressing tool and may be raised out of operating position.

The modified form of cutter 146 shown in Figs. 14 and 15 has a head 156 with a plurality of arcuate leaf springs 158 attached to the underside of the head by screws 159. Blades 157 are secured to the free ends of the leaf springs. To regulate the tension of the springs, each is provided with a shiftable fulcrum 160 interposed between the same and the cutter body and being in the form of an interned ear on a ring 161 mounted for rotative adjustment on the body by screw and slot connections 162 to shift the fulcrums in varying the effective lengths of the springs. The springs may be received in recesses 163 in the ears 160 whereby the ears will further serve to hold the springs against edgewise movement during the dressing operation.

The springs insure that the blades will remain in contact with the ware surface where there are variations in the level of the ware surface on which the tools are operating. For instance, where the tool is being operated near the brim of a piece of flatware, oppositely disposed blades are alternately aligned tangentially and laterally of the conical or sloping side of the ware as they rotate thereof in the path of the burrs. The springs will cause the blades to remain in intimate contact with the surface, although the operating lever of the blades will vary during a complete revolution about the axis of the motor shaft.

With reference to Fig. 17, I have shown herein what a burr may look like after it has been cracked off and smoothed down by the edged burr removing implements. A low prominence X sometimes remains which is not unsightly and which is smooth to the touch.

With reference to Fig. 18, I have shown therein what a burr may look like after it has been cracked off by the edged burr removing tools and/or ground down by the grinding implements. A low prominence Y, substantially flat on top and almost flush with the surrounding surface of the ware and therefore barely noticeable remains.

Any one of the grinding wheels shown and described herein may have the grinding surface thereof composed of industrial diamonds or the like in order to reduce tool wear and eliminate the need for frequent adjustment to compensate for wear.

It will be understood that the holder for the edged tools may be pivotally mounted on its supporting arm for swinging movement in one direction, movement in the other direction being arrested by a stop. This arrangement is advantageous where the tool or ware is oscillated, the object being to produce a working stroke and an idle stroke, the tool simply riding over the burr on the idle stroke.

Obviously, the method and apparatus hereof would remove from the ware any other unwanted protuberances which project above the level of the surface of the ware, for instance stray bits or scraps of clay which may escape the sponger's notice and become glazed over in firing. Ordinarily, the piece would be rejected for imperfections of this character, however with the present method and apparatus, these protuberances would also be removed along with the burrs thereby rendering salable a piece which might

otherwise be scrapped. Protuberances of this description may also be called "burrs" and it is to be understood that the term "burrs" is to encompass protuberances of this description.

I claim:

1. A pottery dressing machine having a burr removing implement for detaching burrs from the glazed, hardened surface of a fired ware piece, a floating mounting for said implement enabling it to float up and down on the surface of the ware and pass smoothly thereover in position to act upon the burrs projecting thereabove, a ware support, manually operated means for relatively moving the ware support and implement support to bring the implement and ware into deburring position, and means for oscillating the ware support and implement support, either one or both to effect the removal of burrs by oscillatory motion.

2. A pottery dressing machine having an angularly movable burr removing implement for detaching the burrs from the back of glazed, hardened potteryware, a counterbalance for supporting some of the weight of the implement to permit it to pass smoothly over the surface of the ware and manually actuated means for feeding the ware to the implement.

3. A pottery dressing machine having an oscillatable, angularly movable burr removing implement for detaching the burrs from the back of glazed, hardened potteryware, a counterbalance for supporting some of the weight of the implement to permit it to follow surface irregularities of the ware and pass smoothly thereover, means for controlling the amount and speed of oscillation and manually actuated means for feeding the ware to the implement.

4. A pottery dressing machine having an oscillatable, angularly movable burr removing implement for detaching the burrs from the back of glazed, hardened potteryware, a counterbalance for supporting some of the weight of the implement to permit it to follow surface irregularities of the ware and pass smoothly thereover, means for controlling the amount and speed of oscillation and manually actuated means for feeding the ware to the implement, including means for oscillating the ware.

5. A pottery dressing machine having an oscillatable, angularly movable burr removing implement for detaching the burrs from the back of glazed, hardened potteryware, a support for said implement, an adjustable counterbalance for supporting the weight of the support and implement to thereby permit the implement to rest on the surface of the ware and pass smoothly thereover while following surface irregularities, a variable speed drive for oscillating said support and manually actuated means for feeding the ware to the implement.

6. A pottery dressing machine having an oscillatable, angularly movable burr removing implement for detaching the burrs from the back of glazed, hardened potteryware, a pivoted support for said implement on which the implement is movable to various positions of adjustment relative to the ware, an adjustable counterbalance for predetermining and controlling the pressure of the implement against the work, means for oscillating the support, means for regulating the speed of oscillation, a manually operable means for feeding the ware to the implement and means for oscillating said ware, the burrs being removed by oscillatory motion between the implement and ware.

7. A pottery dressing machine having an oscil-

latable, angularly movable burr removing implement for detaching burrs from the back of glazed, hardened potteryware, a pivoted support for said implement on which the implement is movable to various positions of adjustment, a holder for said support rotatable about an axis, a rack and gear for oscillating said support, an adjustable speed drive for oscillating said rack, a manually operable means including a ware support for feeding the ware to the implement and an adjustable speed drive for rotating said ware support operated in conjunction with said ware feeding means.

8. A pottery dressing machine having dressing means including a rotatable burr removing implement mounted for oscillation about a given axis and for angular movement about another axis, a pivoted support for said implement, a counterbalance for supporting some of the weight of the dressing means to permit the dressing means to pass smoothly over the surface of the ware, means for oscillating said support including an adjustable speed drive, a ware support and manually operated means for rotating it.

9. A pottery dressing machine having ware dressing means including a rotatable grinder for grinding down burrs projecting above the surface of glazed, fired potteryware and a member associated with said grinder having an edged surface for chipping off burrs and for spacing said grinder above the surface of the ware, a pivoted holder for said dressing means, a counterbalance for supporting some of the weight of said dressing means to permit it to ride smoothly over the ware surface, means for supporting the ware and manually operated means for feeding the ware to the dressing means.

10. A pottery dressing machine having a plurality of burr removing implements arranged in a circle about a given axis, means for oscillating said implements, about said axis, a pivoted support for each implement, means associated with each support for counterbalancing the weight thereof and permitting the implements to move angularly up and down about the pivot as irregularities in the surface of the ware are encountered, a ware support, means for moving the ware support toward and away from said implements and means for rotating said ware support including a manually operable drive therefor.

11. A pottery dressing machine having an implement for detaching burrs from the back of glazed fired potteryware, a holder from which said implement is resiliently suspended to permit the implement to strike the burrs a side blow and ride over the stub, means for rotating the holder, a pivoted support for said holder having a counterbalance associated therewith, means for oscillating said support and manually operated means for feeding the ware to said implement.

12. A pottery dressing machine having an implement holder, means for rotating said holder, a support for said holder, a counterbalance for supporting some of the weight of said holder, means for oscillating said support, an implement attached to said holder by a resilient connection, a ware support and manually operated means for moving said support relative to said implement.

13. A pottery dressing machine having an implement holder, means for rotating said holder, a support for said holder, a counterbalance for supporting some of the weight of said holder, means for oscillating said support, an implement attached to said support having a plurality of chisel-like formations, means for rotating said implement, a ware support and manually oper-

ated means for moving said support relative to said holder.

14. A pottery dressing machine having a dressing implement, a support therefor, a ware support therebelow, including means operable to center the ware thereon including a plurality of grippers engageable with the peripheral zone of the ware and actuated upon movement of the ware into and out of dressing position to grip and release the ware, a shaft on which said ware support is mounted, means for rotating said shaft including a pedal actuated drive mechanism and means slidably connected to said shaft for raising and lowering the ware support relative to the implement.

15. A pottery dressing machine having a dressing implement, a support therefor, an elevatable ware support therebelow including suction means for gripping the ware thereto and ware centering means, means for operating said suction means and said ware gripping means upon elevation of the ware support, a shaft on which said ware support is mounted, a dashpot for resisting movement of the shaft in one direction, pedal operated mechanism for rotating said shaft and manually operated means for raising and lowering said ware support relative to said implement.

16. In combination, a rotatable burr removing implement and a rotatable and reciprocable ware support therebelow, said ware support having means for centering the ware thereon and gripping the ware thereto, a cable operated drive for rotating said ware support and a manually operated means for reciprocating said ware support.

17. A pottery deburring machine comprising a burr removing implement for removing burrs from the glazed, hardened surface of fired pottery-ware, means for feeding said ware toward said implement comprising a manually movable ware support, a movable implement support arranged to permit the implement to rest on and ride smoothly over the surface of the ware without harming it and to follow the surface irregularities so as to remain in contact with said surface in position to intercept and remove burrs, and means for centering the ware on said support.

18. A pottery deburring machine comprising a burr removing implement for detaching burrs from the glazed, hardened surface of fired potteryware, means for feeding said ware toward said tool comprising a manually movable ware support having associated therewith means for rotating the support, a movable implement support above the ware support including an angularly movable implement holder arranged to permit continuous variation in the angular position of the implement relative to the pivotal axis of the holder to enable the implement to follow the ware surface regardless of irregularities therein and to shear across the burrs at the level of the surface of the ware.

19. Apparatus for deburring glazed, fired potteryware comprising, in combination, a deburring implement and an angularly movable support for said implement constructed and arranged to allow the implement to pass smoothly over the glazed surface of the ware without acting thereon and to act on the burrs projecting thereabove, a ware support and manually operated means for moving one of the supports relative to the other to move the ware and implement into deburring relation.

20. Apparatus for deburring glazed, fired potteryware comprising, in combination, a deburring implement and a support for said implement constructed and arranged to allow the implement to pass smoothly over the glazed surface of the ware without acting thereon and to act on the burrs projecting thereabove, a ware support, manually operated means for moving one of the supports relative to the other to move the ware into deburring position and means for moving the implement and ware relative to one another to effect a deburring operation.

21. Apparatus for deburring glazed, fired potteryware comprising, in combination, a deburring implement and a floating support for said implement formed to allow the implement to pass harmlessly over the glazed surface of the ware and act upon the burrs projecting thereabove, a ware support, manually operated means for moving one of the supports relative to the other to bring the implement and ware into deburring position and means for moving the implement and ware relative to one another to effect a deburring operation.

22. Apparatus for deburring glazed, fired potteryware comprising, in combination, a deburring implement and a support for said implement formed to allow the implement to pass smoothly over the glazed surface of the ware without acting thereon and to act on the burrs projecting thereabove, a ware support, means for angularly moving one of the supports relative to the other to effect a deburring operation and manually operated means for moving one of the supports relative to the other to bring the ware and implement into deburring position.

23. Apparatus for deburring glazed, fired potteryware comprising, in combination, a deburring implement in the form of a chisel like tool, a support for said tool formed to allow it to pass smoothly over the glazed surface of the ware without acting thereon and to act on the burrs projecting thereabove, a ware support, means for angularly moving one of the supports relative to the other to effect a deburring operation and manually operated means for moving one of the supports relative to the other to bring the ware and implement into deburring relation.

24. Apparatus for deburring glazed, fired potteryware comprising, in combination, a deburring implement in the form of a grinder, support means for said grinder formed to allow it to pass over the glazed surface of the ware without acting thereon and to act on the burrs projecting thereabove, a ware support, means for angularly moving one of the supports relative to the other to effect a deburring operation and manually operated means for moving one of the supports relative to the other to bring the ware and implement into deburring relation.

25. Apparatus for deburring glazed, fired potteryware comprising, in combination, a deburring implement and a support therefor constructed and arranged to allow said implement to pass smoothly over the glazed surface of the ware without acting thereon and to act on the burrs projecting thereabove, a ware support, manually operated means for moving one of the supports relative to the other to bring the ware and deburring implement into deburring relation and means for angularly moving both of the supports to effect deburring of the ware.

WILLIAM J. MILLER.
